UNITED STATES PATENT OFFICE.

MAURICE HORAN, OF WATERBURY, CONNECTICUT, ASSIGNOR TO WATERBURY MFG. CO., OF WATERBURY, CONNECTICUT, A CORPORATION.

BUFFING-MACHINE ATTACHMENT.

1,295,031.

Specification of Letters Patent.

Patented Feb. 18, 1919.

Application filed August 7, 1918. Serial No. 248,663.

To all whom it may concern:

Be it known that I, MAURICE HORAN, a citizen of the United States, residing at Waterbury, in the county of New Haven and 5 State of Connecticut, have invented a new and useful Improvement in Buffing-Machine Attachments; and I do hereby declare the following, when taken in connection with the accompanying drawings and the characters of reference marked thereon, to be a full, 10 clear, and exact description of the same, and which said drawings constitute part of this application, and represent, in—

Figure 1 a broken view in side elevation 15 of my improved attachment applied to a buffing machine of ordinary type.

Fig. 2 a view in longitudinal section on the line 2—2 of Fig. 1.

Fig. 3 a detached sectional view on the 20 line 3—3 of Fig. 1.

Fig. 4 a detached end view of the double chuck-carrier, shown as disassembled.

Fig. 5 a similar view showing the same 25 part, assembled.

My invention relates to an improved buffing machine attachment, the object being to permit the simultaneous buffing of two pieces of work at one and the same time from one main buffing-spindle.

With these ends in view, my invention consists in a buffing machine attachment having certain details of construction as will be hereinafter described and pointed out in the 30 claims.

In carrying out my invention as herein shown, I employ a double, chuck-carrier having two bearing-sleeves 4 and 5 and a split clamping-sleeve 6, these three sleeves being cast in one piece and united by webs 7, 8 and 9, and the bearing or chuck-sleeves being 35 sufficiently separated from each other to permit the buffing-wheel (not shown) to enter part way between them. The offsetting lugs 10 and 11 of the split-sleeve 6 are provided with clamping bolts 12 furnished with nuts 13. The said double chuck is also formed with a socket 14 receiving a crank-pin 16 secured in place by a set-screw 16 and carrying a washer 17 and a nut 18, which latter is screwed upon the threaded end 19 of the pin 15. The said carrier is by its split-sleeve 6 clamped upon the forward end of a reciprocating sleeve 20 (Fig. 2) which is mounted for reciprocation, within narrow limits, upon the main buffing-spindle 21

which projects forward through it for the reception of a driving gear 22 secured to the said spindle by a key 23. The reciprocating sleeve 20 has bearing in the upper end of an arm 24 forming a part of the machine-frame and is prevented from turning in the said arm by means of a key 25 which does not prevent the sleeve from reciprocating with respect to the arm. The driving gear 22 aforesaid, meshes into and simultaneously 60 drives chuck-gears 25 respectively secured to the projecting ends of flanged rotary bushings 27 (Fig. 3) located within the bearing-sleeves 4 and 5, by means of keys 28 and nuts 29. These bushings receive threaded 65 chuck-spindles 30, the projecting inner ends of which are provided with hand-wheels 31 secured in place by set screws 32, while their unthreaded forward ends project beyond the gears 25 and are provided with tapering 70 chuck-spreaders or heads 33 of any approved construction, it being understood that the projecting forward ends of the spindles 30 receive and support the chucks whatever 75 their character, in which the work is mounted. The spreaders 33 will be moved in one direction or the other as required for opening and closing the chucks, by means of the hand-wheels 31.

Under the construction described, the two 80 chucks are simultaneously rotated at the same speed by means of the spindle 21, whereas in the buffing attachments of the prior art, only one chuck has been operated. It will also be understood that the rotation 85 of the gears 25 rotates not only the spindles 30, but also the bushings 27 and the hand-wheels 31. For imparting a transverse movement to the work with respect to the buffing-wheel, I may employ any of the well 90 known mechanisms for that purpose. As herein shown, the carrier is connected by a rod 34 attached to the crank-pin 15 and a spring 35, to a connecting-rod 36 the outer 95 end of which is connected to a cam-disk 37 having a radial slot 38 which provides for varying the throw of the main spindle and the carrier, and hence of the chucks and the work carried thereby. The said disk 37 is connected by suitable gearing to the 100 driving shaft 30 which is also connected by gearing with the main spindle 21 which is thus simultaneously rotated and reciprocated.

In using my improved buffing attach- 110

ment, two articles to be buffed are mounted in the chucks respectively applied to the chuck-spindles 30. Then when the machine is started, the articles carried by the respective chucks are simultaneously moved lengthwise with respect to the buffing wheel and also revolved. Under this construction, one buffing wheel may be utilized for simultaneously buffing two articles with no increased expense above the initial cost of the double fixture.

While I have shown my improved buffing attachment applied to one form of buffing machine, I would have it understood that I do not limit myself to such a buffing machine as herein shown and described, but hold myself at liberty to use my attachment with any machine to which it may be attached.

I claim:—

20. 1. A buffing machine attachment comprising a double one-piece chuck-carrier having two chuck-bearing sleeves separated as required to permit the partial entrance of a buffing-wheel between them and each mounting an adjustable chuck-spindle provided at its rear end with a gear-wheel and at its forward end with a chuck-spreader, and the said carrier also having a clamping-sleeve by which the carrier is mounted upon 30 the main buffing spindle of the machine, a

gear connecting the main spindle with the respective gears of the chuck-spindles, and means for rotating the main-spindle and for reciprocating it.

2. In a buffing machine, the combination 35 with the main buffing-spindle thereof, of a non-rotatable sleeve mounted for reciprocation thereon, a double one-piece chuck-carrier mounted upon the said sleeve and comprising a clamping-sleeve and two chuck-bearing sleeves which latter are arranged to permit the partial entrance of a buffing-wheel between them, chuck-spindles mounted in the said bearing-sleeves and each provided at its rear end with a gear wheel and 40 at its forward end with a chuck-spreader, a gear mounted upon the spindle and meshing into the said gears on the chuck-spindles for simultaneously rotating the same, and means connected with the double chuck-carrier for reciprocating the same simultaneously with the rotation of the chuck-spindles. 45

In testimony whereof, I have signed this specification in the presence of two subscribing witnesses.

MAURICE HORAN.
